UNITED STATES PATENT OFFICE.

NILS KILDAHL, OF HORTON, MONTANA.

PIN-FASTENER.

1,391,480.

Specification of Letters Patent. Patented Sept. 20, 1921.

Application filed September 10, 1918. Serial No. 253,443.

To all whom it may concern:

Be it known that I, NILS KILDAHL, a citizen of the United States, residing at Horton, in the county of Custer and State of Montana, have invented certain new and useful Improvements in Pin-Fasteners, of which the following is a specification.

This invention relates to a fastening device, and is directed particularly to an article for this purpose in the form of a pin designed particularly for fastening together, two or more sheets of paper.

The primary object of the invention is to provide a pin like article with a flat head to serve as a paper fastener that will be simple, inexpensive and efficient for the purpose designed and especially so when it is employed to secure sheets of paper together for mailing, the flat head of the improved pin permits the papers to be more closely folded and will not cut or mar the surrounding paper when subjected to pressure.

With this object in view, together with others which will appear as the description proceeds, the invention resides in the novel formation, combination and arrangement of parts, all as will be described more fully hereinafter, particularly pointed out in the claim, and illustrated in the accompanying drawings in which—

Figure 1 is a perspective view of two sheets of paper secured together by the improved fastening device.

Fig. 2 is an elevation, enlarged, of the improved fastener, and

Fig. 3 is also an elevation of the fastener, enlarged, seen at a right angle to Fig. 2.

In the drawing, 10 indicates the shank of the pin fastener which is made of wire, preferably of round cross section and pointed

at one end as at 11. At its opposite end the shank is flattened in the plane of the shank to form a circular or disk like head 12 having a thickness less than the thickness of the shank 10, and a diameter about three times 45 as great; *i. e.* substantially the same as the diameter of the head of an ordinary round headed pin as shown in dotted lines in Fig. 2.

A pin fastener formed with a head such as described will lie, when in use, with the 50 flat side of the head against the articles secured; and as said head is of less thickness than the shank, it will bear lightly, if at all, on such articles which, if of paper, will not be disfigured by the head projecting beyond 55 the shank as in the case of an ordinary pin, see dotted lines, Fig. 3.

The foregoing description and the drawings have reference to what may be considered the preferred, or approved form of my 60 invention. It is to be understood that I may make such changes in construction and arrangement and combination of parts, materials, dimensions, et cetera, as may prove expedient and fall within the scope of the 65 appended claim.

Having thus fully described my invention, what I claim as new and desire to secure by Letters Patent, is:—

In a paper fastener, a pin having a disk-shaped head the flat side of the disk being substantially coplanar with the side of the pin but of lesser thickness than the diameter of the pin.

In testimony whereof I affix my signature 75 in presence of two witnesses.

NILS KILDAHL.
